UNITED STATES PATENT OFFICE.

NATHAN KASDAN, OF BRONX, AND DANIEL POLLACK, OF BROOKLYN, NEW YORK, AS
SIGNORS TO MAJESTIC METAL SPECIALTIES, INC., OF NEW YORK, N. Y., A CORPORA-
TION OF NEW YORK.

COSMETIC-STICK HOLDER.

Application filed December 16, 1927. Serial No. 240,440.

Our device refers to containers, or holders, especially adapted for use with cosmetic sticks, such as lip sticks, eyebrow pencils and similar articles.

5 In devices of this character it is desirable that they be compact, capable of easy manipulation, protective to the cosmetic when not in use, economic in cost of protection and of such construction that the cosmetic 10 may be readily positioned for application.

The device of our invention possesses all of the above mentioned, and other, valuable and desirable attributes as will be evident from a consideration of our specification and 15 its accompanying drawings.

In the accompanying drawings illustrating modified forms of the device of our invention, similar parts are designated by similar numerals.

20 Figure 1 is a perspective view of one form of the device of our invention in closed position.

Figure 2 is a section through the line 2—2 of Figure 1.

25 Figure 3 is a section through the line 3—3 of Figure 1.

Figure 4 is a longitudinal section of the device of Figure 3, in open position with the cosmetic stick extended.

30 Figure 5 is a perspective view of a modified form of the device of our invention in closed position.

Figure 6 is an enlarged longitudinal section of the device of Figure 5.

35 Figure 7 is a view of Figure 6 in open position and with the cosmetic stick extended.

The particular form of the device of our invention shown in Figures 1 to 4 inclusive

40 comprises a casing 10, open at the top and closed at the bottom and having the longitudinal opening 11.

A cover member comprises the slidable member 12 hingedly attached to the member 45 13 at 14. The upper portion of the member 13 has a cover 15, capable of placement over the open end of the casing 10, the cover 15 having the tip 16.

The slidable member 12 has two tongues, 50 or prongs, 17, 17 extended through the opening 11 and through the side of a pencil, or lip stick, carrier 18, containing a lip stick 19.

The prongs 17, 17 thus act to retain the member 12 in slidable position upon the 55 casing 10, and at the same time cause the

lip stick carrier 18 to move longitudinally within the casing 10 with the slidable movement of the member 12.

The operation of the device is as follows:—

60 The device when not in use is in the position shown in Figures 1 and 3. When it is desired to use the lip stick, the slidable member 12 is moved upwardly thus moving the lip stick 19 outwardly of the casing 10, 65 and at the same time the member 13 of its own weight revolves upon the hinge 14 into the positions shown in Figure 4 thus allowing the use of the lip stick. To close the device, it is tilted to one side causing the 70 member 13 to abut upon the casing 10 and the slidable member 12 is moved downwardly.

75 In the modification shown in Figures 5, 6, and 7, the casing 10 is of rectangular shape, and the cover member comprising the slidable member 20 is hinged at 21 through the opening 11 to the lip stick carrier 18.

80 In the operation of this modified form the slidable member 20 is moved upwardly the release of the member 20 allowing it to fall into open position as shown in Figure 7.

85 It will thus be noted that our device comprises a lip stick, or cosmetic stick, holder of such construction that the upward movement of a slidable member will open the device, move the cover into operative position and expose the contents for use.

90 We do not limit ourselves to the particular size, shape, number or arrangement of parts as shown and described as these are given simply as a means for clearly describing the device of our invention.

95 What we claim is:—

1. In a cosmetic stick container, in combination, a casing having a longitudinal opening therein, a slidable member exterior of the casing, a cover member hingedly attached to the slidable member, a slidable cosmetic stick carrier within the casing, and means within the casing opening connecting said slidable member with said carrier. 100

2. In a cosmetic stick container, in combination, a tubular casing having a longitudinal opening therein, a slidable member encompassing a portion of said casing, an extended cover member encompassing a portion of said casing exterior thereof and hingedly attached to said slidable member, a slidable cosmetic stick carrier within the 110

casing and means within the casing opening connecting said carrier with said slidable member.

3. In a cosmetic stick container, in combination, a tubular casing having a longitudinal opening therein, a slidable member encompassing a portion of said casing, an extended cover member encompassing a portion of said casing exterior thereof and ¹⁰ hingedly attached to said slidable member,

a slidable cosmetic stick carrier within the casing and pin means within the casing opening connecting said carrier with said slidable member.

Signed at New York city, in the county ¹⁵ of New York and State of New York, this 14th day of December, 1927.

NATHAN KASDAN.
DANIEL POLLACK.
